UNITED STATES PATENT OFFICE

LAWRENCE M. PERSONS, OF QUINCY, ILLINOIS

WATER SUPPLY REGULATOR

Application filed April 10, 1931. Serial No. 529,107.

It is now recognized as desirable to provide hot air furnaces with a humidifier to supply moisture to the heated air before delivery to the distributing system instead of depending upon individual evaporating pans at the points of discharge, which individual pans are often neglected with resulting abnormally dry air supply. When such furnace humidifiers are used, it is desirable to provide a thermostatically controlled "drip water" supply regulator to automatically govern the flow of water thereto. Up to the present time, as far as I am aware, no such drip water supply regulator has been devised which is wholly satisfactory both from the standpoint of mechanical construction and reliability of operation.

It is the object of my invention to provide a drip water supply regulator which will be both simple in construction and reliable in operation and which will not supply an excessive amount of water when abnormally heated, nor injure the valve mechanism when abnormally cooled.

In the accompanying drawing, which illustrates one form of drip water supply regulator made in accordance with my invention, Figure 1 is a vertical longitudinal section on an enlarged scale; Figure 2 is a cross section taken on the lines 2-2 of Figure 1; and Figure 3 is a side view on a reduced scale.

The body of the device consists of a cylindrical casing or barrel 1 provided with a flange 2 having bolt or screw holes 3 by means of which it is secured to a wall of the furnace. Threaded into the inner end of the barrel is an aluminum sleeve 4 adapted to project through the wall into the furnace. The inner end of the sleeve is closed by a screw plug 5 having a threaded central opening to receive the inner end of a steel rod 6 which, after being properly adjusted, is secured against movement by a lock-nut 7. As the materials of the sleeve and the rod have different coefficients of expansion, these parts form the elements of a thermostatic couple the relative response of which to changes in temperature govern the valve mechanism of the device.

The rod is supported near its outer end by a guide 8 and its end face bears against one

end face of a floating valve member 9 sliding in the sleeve 4 which forms a guide therefor. The valve member is provided with a shoulder 29 adapted to strike against the end of the sleeve 4 and thus determine the maximum opening of the valve. This maximum opening may be regulated by adjusting the rod longitudinally in the plug 5 so that the shoulder 29 will be a greater or less distance from the sleeve when the parts are at normal temperature. The opposite end of the valve member is in the form of an annulus 10 having a central water port 11 and the face of which forms a valve seat cooperating with a resilient washer 12 surrounding a pin 13 carried by a plug 14 threaded into the outer end of the barrel. A lock nut 15 serves to hold the plug in adjusted position. Pin 13 projects beyond the washer 12 and enters the port 11. It is, however, slightly smaller than the port so as to provide a space forming part of the water passage through the device. The flange 16, which embraces the outer edge of the washer 12, projects beyond the washer and is of somewhat larger diameter than the plug in order to form a second annular water passage. The object of extending the pin and flange beyond the face of the washer is to provide retaining walls to prevent displacement of any of the material of the washer under pressure, and to provide means for guiding the valve member in addition to its engagement with the tube 4.

Port 11 communicates with a supply nipple 17 which is threaded into the valve member and projects through an elongated opening 18 in the barrel. This nipple is connected by a union 19 with a pipe 20 leading to the water supply. When the water pressure is sufficient it may be depended upon to force the valve member away from its seat when permitted to move by retraction of the rod 6, but I prefer to place a coil spring 21 between the end of the plug 14 and a shoulder on the valve member to insure prompt movement of the latter under all conditions of water pressure.

Depending from the barrel is a discharge tube 22 provided with sight openings 23. This tube communicates with the interior of the barrel through a restricted passage 24, the

lower end of which is surrounded by a lip 25 to insure the dripping of the water centrally through the tube past the eight openings instead of running down the walls of the 5 tube. The end of the tube has threaded into it a discharge nipple 26 connected by a union 27 to a pipe 28 leading to the humidifier pan in or adjacent to the furnace.

In the operation of the device, when the furnace is cold the end of the annulus 10 will bear 10 against the washer 12, thus preventing the passage of water through the device. The exact temperature at which the water flow is cut off is determined by the adjustment of 15 the plug 14. When the thermostatic couple is heated the rod 6 will be retracted, allowing the valve to open so that water may pass through the valve into the barrel and thence through discharge tube 22 to pipe 28 leading 20 to the humidifier. As the water drips past the eight openings 23 the operation of the device is at all times under inspection. As soon as the shoulder 29 strikes the sleeve 4 the maximum flow is reached so that further 25 retraction of the rod 4 does not further increase the flow, thus flooding of the device under abnormally high temperature is avoided. This desirable result is due to the fact that the thermostatic element is so arranged 30 as to open the valve under increase of temperature instead of closing it under such condition, as is the usual practice; and to the further fact that the rod of the thermostat is not attached to the valve member but is capable 35 of movement away from it after it is stopped by contact of the shoulder 29 with the end of the tube. In case the device is subjected to unusually low temperature the resilient washer will be compressed, thus compensating for 40 the abnormal forward movement of the valve member without injury to the parts. The compression of the washer is possible due to the fact that being both internally and externally supported it may be made of considerable 45 thickness and of quite resilient material and yet perform the function without liability of permanent distortion by the action of the valve.

Having fully described my invention, what 50 I claim as new and desire to secure by Letters Patent of the United States is:

1. In a device of the class described, the combination with a casing, of a valve member movable longitudinally in said casing, a 55 sleeve carried by said casing and forming one element of a thermostatic couple, a rod in said sleeve forming the other element of the thermostatic couple, said rod bearing against one end of said valve member but capable of retractile movement independently thereof, means for adjusting said rod longitudinally, an adjustable member carrying 60 a valve seat co-operating with the other end of valve member to check the flow of water 65 through the device, and a stop for limiting

the movement of said valve member away from the valve seat to determine the maximum flow of water through the device.

2. In a device of the class described, the combination with a casing, of a valve member in said casing, thermostatic means for actuating said member, a supply nipple carried by said valve member and projecting through the wall of the casing, said nipple being capable of moving with the member 70 relative to the casing, a port in the valve member communicating with the interior of the casing, a valve seat cooperating with the valve member to open and close said port, and a discharge passage leading from the interior of the casing.

3. In a device of the class described, the combination with a casing, of a valve member in said casing, thermostatic means for actuating said member, a supply nipple carried by said valve member and projecting through the wall of the casing, said nipple being capable of moving with the member relative to the casing, a port in the valve member communicating with the interior of the casing, a compressible valve seat cooperating with the valve member to open and close said port, and a discharge passage leading from the interior of the casing.

4. In a device of the class described, the combination with a casing, of a valve member in said casing, thermostatic means for actuating said member, a supply nipple carried by said valve member and projecting through the wall of the casing, said nipple being capable of moving with the member relative to the casing, said valve member being provided with a port communicating with the interior of the casing, an adjustable plug in said casing provided with a valve seat cooperating with said valve member to open and close said port, and a discharge passage leading from the interior of the casing.

5. In a device of the class described, the combination with a valve casing, of a valve member in said casing and provided with a supply passage, thermostatic means for actuating said member, said member having an annulus, the central opening of which communicates with said supply passage and through a port with the interior of the casing, an adjustable plug in said casing, said plug being provided with a valve seat cooperating with said annulus to open and close said port, and a discharge tube communicating with the interior of the casing, said tube being provided with a sight opening.

6. In a device of the class described, the combination with a casing, of a valve member in said casing, thermostatic means for actuating said member, a supply nipple carried by said member and projecting through the wall of the casing, said nipple being capable of movement with the member relative to

the casing, said member having an annulus the central opening of which communicates with said supply nipple and through a port with the interior of the casing, an adjustable plug in said casing, said plug being provided with a valve seat cooperating with said annulus to open and close said port, and a discharge tube communicating with the interior of the casing, said tube being provided with

10 a sight opening.

7. In a device of the class described, the combination with a casing, of a valve member in said casing, a sleeve carried by said casing and forming one element of a thermostatic couple, a rod in said sleeve forming the other element of the thermostatic couple, said rod actuating said valve member but capable of retractile movement independently thereof, means for adjusting said rod longitudinally, a supply nipple carried by said valve member and projecting through the casing, said nipple communicating with the interior of the casing through the valve face of the valve member, an adjustable member having a valve seat cooperating with said valve face, and a discharge tube leading from the interior of the casing and provided with a sight opening.
